SOUND PROPAGATING APPARATUS

John Hays Hammond, Jr., Gloucester, Mass.

Application April 11, 1944, Serial No. 530,448

5 Claims. (Cl. 35—25)

This invention relates to sound producing apparatus and more particularly to apparatus for picking up and reproducing the sound of a vessel's propeller.

In particular the invention provides means for picking up the sound of a vessel's propellers, amplifying the same and reproducing the amplified sound at a distance from the vessel.

The invention also consists in certain new and original features of construction and combinations of parts hereinafter set forth and claimed.

Although the novel features which are believed to be characteristic of this invention will be particularly pointed out in the claims appended here-to, the invention itself, as to its objects and advantages, the mode of its operation and the manner of its organization may be better understood by referring to the following description taken in connection with the accompanying drawing forming a part thereof, in which

Fig. 1 illustrates diagrammatically the pick-up, amplifying and sound propagating apparatus embodying the present invention; and

Fig. 2 is a cross section of the sound reproducing apparatus taken on line 2—2 of Fig. 1.

Like reference characters denote like parts in the several figures of the drawing.

In the following description parts will be identified by specific names for convenience, but they are intended to be as generic in their application to similar parts as the art will permit.

Referring to the accompanying drawing and more particularly to Fig. 1 a vessel 11 is provided with the usual propeller 12 and rudder 13. Mounted on the hull of the vessel 11 and adjacent to the propeller 12 is a microphone 14 which is connected by conductors 15 to the input circuit of an amplifier 16, which may be of any well known and standard construction. The output circuit of the amplifier 16 is connected by a cable 17 to a pair of loud speakers 18, mounted in a "fish" 19 which is towed a considerable distance behind the vessel 11 by means of the cable 17. The speakers 18 are positioned to impress compressional waves onto the surrounding water. The speakers are preferably mounted in the fish 19 and are connected to drive one or more external diaphragms 20 which are in contact with the water but are waterproof and prevent the sea water from affecting the speaker itself.

The fish 19 is shown as provided with diving planes 21 and tail fins 22 and may be similar in construction to the fish shown in U. S. Patent No. 1,625,245, issued April 19, 1927, to H. G. Dorsey.

Operation

In the operation of this invention the microphone 14 picks up the noise produced in the water by the propeller 12 and also any noises emanating from the hull of the vessel 11. The energy from the microphone 14 is fed over the conductors 15 to the input circuit of the amplifier 16. This energy is then amplified by the amplifier 16 and the output energy is fed thru the cable 17 to the loud speakers 18 where it is broadcast thru the water as compressional waves emanating from the fish 19. The amplifier is preferably capable of producing sufficient energy to produce compressional waves of an intensity 15 greater than those produced by the vessel 11.

In this way a sound producing apparatus is provided at a considerable distance behind the vessel, so that any sound detecting devices, either on enemy submarines or on sound controlled torpedoes will mistake the sound produced by the loud speakers 18 for the sound produced by the vessel's propeller 12 and will cause the torpedo to be directed at the fish 19 rather than at the vessel 11.

Although only one of the various forms in 25 which this invention may be embodied has been shown herein, it is to be understood that the invention may be embodied in various forms without departing from the spirit of the invention as defined by the appended claims.

30 What is claimed is:

1. Apparatus for protecting vessels, comprising a member to be towed a substantial distance behind said vessel, a compressional wave generator on said member responsive to received energy and having means to produce and propagate compressional waves through the water, means picking up the sound produced by the towing vessel, and means supplying the picked-up sound energy to actuate said generator for reproducing the same as compressional waves of increased intensity in the water.

2. Apparatus for protecting vessels, comprising a member to be towed a substantial distance behind said vessel, a compressional wave generator on said member responsive to received energy and having means to produce and propagate compressional waves through the water, means on the towing vessel to pick up the sound produced thereby, and a transmission channel transmitting the picked-up energy to actuate said generator for reproducing the same as compressional waves of increased intensity in the water.

3. Apparatus for protecting vessels, comprising 55 a member to be towed a substantial distance be-

hind said vessel, means picking up the sound produced by said vessel and converting the same to electrical energy, means transmitting said electrical energy to said member, means on said member converting said electrical energy to mechanical energy and means responsive to said mechanical energy to propagate compressional waves of increased intensity through the water from said member.

4. Apparatus for protecting vessels, comprising a member to be towed a substantial distance behind said vessel, a compressional wave generator on said member responsive to received energy and having means to produce and propagate compressional waves through the water, a microphone on said vessel positioned to pick up the sound thereof, and a circuit connecting said

microphone to actuate said generator for reproducing the sound as compressional waves of increased intensity in the water.

5. Apparatus for protecting vessels, comprising a member to be towed a substantial distance behind said vessel, a compressional wave generator on said member responsive to received energy and having means to produce and propagate compressional waves through the water, a microphone on said vessel positioned to pick up the sound thereof, an amplifier fed by said microphone and a circuit connecting the output of said amplifier to actuate said generator for reproducing the sound as compressional waves of increased intensity in the water.
